UNITED STATES PATENT OFFICE.

ALEXANDER L. ULLRICH, OF CHICAGO, ILLINOIS.

LEATHER-WATERPROOFING COMPOSITION.

Specification of Letters Patent. Patented Mar. 23, 1920.

1,334,573.

Application filed April 17, 1919. Serial No. 290,777.

No Drawing.

To all whom it may concern:

Be it known that I, ALEXANDER L. ULLRICH, a citizen of the United States, residing at Chicago, in the county of Cook and State 5 of Illinois, have invented certain new and useful Improvements in Leather-Waterproofing Composition, of which the following is a specification.

The invention relates to a composition for 10 treating leather to render the same water-proof without producing any injurious effects and which will not cause the surface of the leather to check or the body of the leather to harden, but which rather will render the leather pliable and increase its period of service.

The composition consists essentially of tar and drip oil, combined in bulk about forty-five per cent. of the oil to fifty-five per cent. 20 of the tar. An odorant is added such as oil of mirbane, oil of sassafras, oil of citronella and the like, one to five per cent. of the odorant being added according to its strength.

The tar may be any bituminous product. 25 The drip oil is a by-product of water gas, the oil being pumped from the drips after the gas has been manufactured.

While the best proportions consist of forty-five per cent. of oil to fifty-five per cent. of the tar the leather water-proofing composition can be obtained from a sliding scale of seventy per cent. of tar to thirty per cent. of oil and vice versa.

The leather to be treated to render it

water-proof should be dipped, entirely submerged in the composition while the latter is still warm which fills the pores of the leather and gives it a shiny polished finish. The leather thus treated besides being made water-proof is improved in quality and appearance and will not check or harden or otherwise deteriorate.

In using this water-proof leather in the manufacture of shoes it increases the lasting qualities of the thread used in stitching. 45 In using nails in water-proofed soles, the leather remains compact and firm and the pores do not open and release the nails, which has been one of the objections to other so-called water-proof composition.

Instead of "drip oil" I may use benzole which is also a by-product in the manufacture of gas. The benzole is a refined product but possesses the same features as the drip oil when used in the composition with tar.

Having thus fully described my invention, what I claim as new and desire to secure by Letters Patent is:—

A leather water-proofing composition, composed of tar fifty-five per cent. and drip oil forty-five per cent.

In testimony whereof I affix my signature in presence of two witnesses.

ALEXANDER L. ULLRICH.

Witnesses:

MARION MUNDT,
Mrs. ALEX ULLRICH.
